UNITED STATES PATENT OFFICE.

GEORGE WALTHEER, OF DAYTON, OHIO.

DESIGN FOR AN AUTOMOBILE TRUCK-WHEEL.

45,097.

Specification for Design.

Patented Dec. 30, 1913.

Application filed April 18, 1913. Serial No. 762,129. Term of patent 14 years.

To all whom it may concern:

Be it known that I, GEORGE WALTHEER, a citizen of the United States, residing at Dayton, in the county of Montgomery and State of Ohio, have invented a new, original, and ornamental Design for an Automobile Truck-Wheel, of which the following is a specification, reference being had to the accompanying drawing, forming a part thereof.

Figure 1 is a side elevation of an auto-

mobile truck wheel, showing my new design and Fig. 2 is a peripheral elevation of the same part in section.

I claim:

The ornamental design for an automobile truck wheel as shown.

GEORGE WALTHEER.

Witnesses:

R. J. McCARTY,
MATTHEW SEIBLER.
